UNITED STATES PATENT OFFICE.

THOMAS McCABE, OF ARNOLD BOROUGH, PENNSYLVANIA.

PLATE-LIFTING MECHANISM FOR ROLLING MILLS.

Application filed August 14, 1925. Serial No. 50,277.

This invention relates to plate lifting mechanisms for rolling mills, and is an improvement on the plate lifting mechanism that forms the subject-matter of my U. S. 5 Patent No. 1,538,251, dated May 19, 1925.

One object of my present invention is to eliminate the segmental racks and co-operating pinions of the mechanism described in my said prior patent without reducing the 10 efficiency of the mechanism.

Another object is to provide a plate lifting mechanism for rolling mills in which the carrier that moves the plates upwardly into position to be grasped by the operator standing in front of the rolls of the mill, follows the contour of the top roll in its upward travel and moves rearwardly a considerable distance away from said top roll in its downward travel when the mill is being used for 20 "breaking down" short bars that are being rolled into packs. Other objects and desirable features of my invention will be hereinafter pointed out.

Figure 1 of the drawings is a vertical longitudinal sectional view of a plate lifting mechanism embodying my present invention, taken on the section line 1—1 of Figure 5, showing the carrier in its discharge position.

Figure 2 is a longitudinally sectional view, 30 taken on the same section line, illustrating how the carrier moves rearwardly a considerable distance away from the top roll of the mill during its downward travel.

Figure 3 is a longitudinal sectional view, 35 taken on the same section line, illustrating the carrier in its receiving position.

Figure 4 is a side elevational view, illustrating the carrier moving into its elevated position.

Figure 5 is a top plan view of the mechanism.

Figure 6 is a front elevational view of the mechanism.

Figure 7 is a top plan view, with the carrier removed, so as to more clearly illustrate the construction of the actuating means for the carrier.

Figure 8 is a bottom plan view of the mechanism.

Figure 9 is a rear elevational view of the mechanism; and

Figure 10 is a detail view, illustrating the clutch that is used to govern the operation of the drive shaft of the mechanism.

My improved plate lifting mechanism comprises a carrier A arranged at the rear

of the rolls α of a rolling mill, and an actuating mechanism for said carrier constructed so as to bodily move said carrier upwardly from its receiving position, shown in Figure 3, into its discharge position, shown in Figure 1, then rearwardly and downwardly into the position shown in Figure 2, and thence back to the position shown in Figure 3. During the upward movement of the carrier A the front end of said carrier follows the contour of the top roll of the mill, but during the downward movement of the carrier the front end of same will either follow the contour of said top roll, or will move rearwardly a considerable distance away from the top roll, depending upon whether long plates or short bars are being rolled in the mill, the actuating mechanism for the carrier being so constructed that the operator in charge of the mill can manipulate a coupling pin so as to disconnect certain parts of said actuating mechanism, and thus cause the carrier to follow the contour of the top roll on its downward stroke, 80 when long plates are to be rolled in the mill.

The carrier actuating mechanism can be constructed in various ways without departing from the spirit of my invention, but it will usually comprise pairs of rock levers B and C oscillatingly mounted on the frame of the mechanism and pivotally connected at one end to a carrier support D, on which the carrier is rockably and reciprocatingly mounted, and a rotatable drive shaft E combined with said rock levers in such a way that said levers will swing upwardly from the position shown in Figure 3 into the position shown in Figure 1, during the first half of the forward revolution of the drive shaft 95 E, and will swing downwardly into the position shown in Figure 2, and thence into the position shown in Figure 3, during the last half of the forward revolution of said drive shaft. Said mechanism also comprises a means for reciprocating the carrier relatively to the carrier support, herein illustrated as consisting of a rock arm F, a spring G and a toggle composed of two links 1 and 2. The frame of the mechanism is composed of a number of vertically-disposed members 3 arranged in parallel relation and rigidly connected together by transversely-disposed bolts or tie bars and spacing devices, and if desired, said frame can be provided with 100 flanged supporting wheels 4 that travel on the rails 5 of a track, thereby enabling the

mechanism to be moved as a unit towards and away from the rolls α of the mill. The drive shaft E of the carrier actuating mechanism, which is arranged horizontally and 5 rotatably mounted in the frame of the mechanism, is provided at one end with a clutch, designated as an entirety in Figure 6 by the reference character H which may be of the type described in my U. S. patent previously referred to, said clutch comprising tripping dogs 6 arranged so that when they are moved 10 in one direction by an operating device 7, shown in Figure 10, a driven member 8 on the drive shaft E will be engaged by a rotatable driving member, and when said dogs are restored to normal position by a spring 9, they will cause said driven member to be 15 disengaged from the driving member. In the operation of the mechanism the clutch 20 H is operated manually to cause the drive shaft E to make one-half a revolution and then come to rest, thereby causing the carrier A to move upwardly into its discharge position, and thereafter said clutch is manually operated so as to cause the drive shaft 25 to make another half revolution, and thus restore the carrier A to its receiving position. At the opposite end of the drive shaft E is a rigid crank arm 10, which is connected by 30 a curved link 11 with an arm 12 secured to a shaft 13 to which the rock lever B is fastened. An elbow lever 13^a is secured to the shaft 13 and one arm of said elbow lever is joined by a horizontally-disposed link 14 to 35 an arm 15 on the rock lever C which is secured to a horizontally-disposed shaft 16, thereby causing the levers B and C to operate in unison when the drive shaft E is in operation. The levers B are pivotally connected by a shaft 17 to the front lower end 40 of the carrier support D, and the levers C are pivotally connected by a shaft 18 to the lower rear end of said carrier support, and in order to assist said levers to move said 45 carrier support upwardly and downwardly, said levers are combined with counterbalancing weights I which are arranged vertically at opposite sides of the path of movement of the carrier A, as shown in Figure 6, the 50 levers C having their ends pivotally connected at 19^a to said weights and one arm of each of the elbow levers 13^a previously mentioned being pivotally connected at 19 to said weights. When the carrier A moves upwardly 55 the counterweights I move downwardly, and when said carrier moves downwardly into its receiving position, said counterbalancing weights are restored to their normal elevated position. Due to the fact 60 that the counterweights I are pivotally connected to the levers C and to the elbow levers 13^a with which the levers B are combined, they tie said levers together and co-operate 65 with the straight links 14 to insure parallel movement of said rock levers.

The carrier A is provided on its underside with a pair of longitudinally-disposed guides 20 that receive rollers 21 on the carrier support D, and the rear end of said carrier is pivotally connected by a horizontally-disposed shaft 22 to the upper end of the rock arm F, previously referred to, that forms part of the means for reciprocating the carrier relatively to the carrier support D. The lower end of said rock arm F is pivotally 70 connected with the rock levers C and is so arranged that when said levers swing upwardly during the upward stroke of the carrier A, said rock arm F will cause the front end of the carrier to tilt downwardly, 75 thereby facilitating the discharge of the plate or bundle of plates from the front end of the carrier over the top roll of the mill. In the form of my invention herein illustrated the rock levers C are provided 80 with adjustable, angularly-disposed extension members 23 that sustain a horizontally-disposed cross shaft 24 which passes through a bearing in the lower end of the rock arm F, said extension members 23 being arranged 85 so that they can be rocked about an axis coincident with the pivotal connection between the carrier support D and the rock levers C and being clamped to said rock levers by bolts 25 that pass through curved 90 slots 26 in said extension members. If it is desired to vary the distance between the front edge of the carrier A and the top roll of the mill, when the carrier is in its discharge position, the bolts 25 can be loosened and the extension members 23 thereafter adjusted so as to vary the angular relationship between the rock levers C and the portions of said extension members which sustain the cross shaft 24 that supports the 95 rock arm F. During the upward movement of said rock arm adjustable stops 27 thereon engage a tail piece 28 on the rear end of the carrier and exert pressure on same in a 100 direction to cause the front end of the carrier to tilt downwardly. Consequently, by adjusting the stops 27 the tilt or angle of the carrier A, when it is in its discharge position, can be varied. The spring G, previously referred to, is connected to the carrier support D, and to the rock arm F, and consequently, exerts pressure on said rock arm in a direction tending to move the carrier A forwardly and hold the rollers 21 105 on the carrier support at the rear ends of the guides 20 on the carrier. Preferably, the rear end portions of said roller guides 20 are curved downwardly at 20^a, as shown in Figures 1 and 3, so that when said carrier is being restored to its receiving position, it will move upwardly relatively to the carrier support D, and thus cause the plate supporting portion of said carrier to move 110 upwardly into engagement with the plate or bar, which at this time is sustained by work 115 120 125 130

supporting members J, hereinafter described, that are arranged at the rear of the rolls of the mill.

The toggle links 1 and 2, previously referred to, which are used to move the carrier A rearwardly away from the top roll of the mill, during the downward stroke of said carrier, are interposed between an adjustable extension member 29 connected with one of the rock levers B, and a rockable member 30 that is oscillatingly mounted on the shaft 24 at one side of the rock arm F and which is combined with said rock arm in such a manner that it moves with same during the downward stroke of the carrier. The extension member 29 is so arranged that it can be rocked about an axis coincident with the pivotal connection between one of the rock levers B and the lower front end 20 of the carrier support to vary the degree of rearward movement imparted to the carrier, and is adjustably connected to said rock lever B by a bolt 31 that passes through a curved slot 32 in said extension member. 25 The toggle links are pivotally connected together by a pivot 33, and the front link 1 is pivotally connected at 1^a to the upper end of the extension member 29 just referred to, the rear toggle link 2 being pivotally connected at 2^a to the rockable member 30 just referred to. Movement is transmitted from the rockable member 30 to the rock arm F by a transmission member K adjustably connected with the rockable member 30 and provided with a shiftable coupling pin 34 that normally is arranged in a hole in one edge of the rock arm F. In the form of my invention herein illustrated the transmission member K is loosely mounted 35 on the hub of the rockable member 30 and is adjustably connected to said member 30 by a clamping bolt 35 threaded into the transmission member and arranged in a curved slot 36 in the rockable member 30. 40 When the coupling pin 34 is disengaged from the rock arm F, the front end of the carrier A will move in a path substantially concentric with the top roll of the mill during the downward stroke of the carrier. 45 Assuming that the carrier A is in its elevated position, shown in Figure 1, and that the coupling pin 34 is in engagement with the rock arm F, the toggle links 1 and 2 virtually act as a strut to transmit movement from the extension member 29 on the rock lever B to the rockable member 30, and the transmission member K transmits movement to the rock arm F when the rock levers B and C swing downwardly from the position shown in Figure 1, thereby causing the carrier A to move rearwardly far enough to cause the front end of same to clear the work supporting members J at the rear 50 of the rolls of the mill, as shown in Figure 2. During the downward movement of the

carrier the tension of the spring G is increased, and just before said carrier reaches the end of its downward stroke, a roller 37 on the toggle link 2 comes into engagement with a portion 38 on the carrier support D, thereby causing the toggle to "break", whereupon the spring G moves the rock arm F and the carrier A forwardly into the position shown in Figure 3. If the mill is being used for rolling long stock, or in other words, is being used for rolling one piece at a time, the coupling pin 34 is disconnected from the rock arm F, for at such times it is not necessary that the front end of the carrier A clear the work supporting members J at the rear of the rolls during the downward stroke of the carrier, because the plate is not passed through the rolls of the mill until the carrier A is in position to receive said plate. The plate receiving portion of the carrier is preferably formed by a renewable wear piece 39 that can be replaced when it becomes badly worn, and said carrier is provided at its rear end with rollers 40 so as to cause the pack to discharge or run off the carrier after being finished. In my improved plate lifting mechanism herein illustrated all that is necessary after the pack has been rolled out to the required length, is to allow the carrier to move downwardly into the position shown in Figure 3 while the operator holds onto the pack. The pack is about once and a half as long as the carrier A, and the operator, by giving it a push rearwardly, will cause it to be discharged from the rear end of the carrier onto the ground or into a receptacle provided for this purpose. Instead of mounting the rollers 21 directly on the carrier support D, I prefer to mount said rollers on a hinged plate 41 on the carrier support. The purpose of constructing the mechanism in this manner is to eliminate breakage of the carrier actuating mechanism in the event the carrier A fails to move rearwardly during its downward travel. In other words, if the means that is used to move the carrier rearwardly during its downward stroke fails to operate, the carrier will strike against the plate or bar on the work supporting members J at the rear of the rolls and will tilt upwardly without causing injury to the mechanism, this, of course, being made possible by reason of the fact that the rollers 21, which are arranged in the guideways 20 on the carrier, are carried by a hinged plate 41 on the carrier support. In order that the carrier A may be adjusted to compensate for wear on the bearings of the bottom roll of the mill, the carrier support D is provided with adjustable stops 42 which support the free end of the hinged roller supporting plate 41. 110 The mechanism comprises a plurality of work supporting members J, previously re- 115 120 125 130

ferred to, which are arranged at the rear of the rolls of the mill for receiving the plate or bar that is passed through the rolls. Said members J are constructed in the form of 5 arms that project rearwardly from a horizontally-disposed rock shaft 43, and means is provided for raising and lowering said arms consisting of a cam 44 on the drive shaft E, a rockable member 45 arranged 10 above said cam and adapted to be raised and lowered by same, and an arm 46 on the rock shaft 43 that co-operates with a roller 47 on the member 45, as shown clearly in Figures 1 to 4. A plurality of stationary 15 members 48, also constructed in the form of arms, are arranged between the members J and project forwardly from same into the space between the rolls of the mill, said members 48 being rigidly secured to a stationary shaft 49 that is preferably carried 20 by brackets secured to the housing of the mill. The cam 44 is so timed that the work supporting members J with a plate supported thereon will swing downwardly into a 25 horizontal position just about the time the carrier A starts on its upward movement. After said carrier starts to move upwardly the cam 44 moves the work supporting members J upwardly into the position 30 shown in Figure 1, and holds said members in this position until the carrier A is restored to its receiving position. As shown in Figure 5, the front end portion of the carrier A is provided with slots 50 arranged 35 so that the members J and 48 will not interfere with the movement of the carrier.

Having thus described my invention, what I claim as new and desire to secure by Letters Patent is:

40 1. A plate lifting mechanism for rolling mills, comprising a work supporting means arranged at the rear of the rolls of the mill for receiving the work discharged from the rolls, a carrier for moving the work upwardly 45 into a position to be discharged forwardly over the top roll of the mill, and an actuating mechanism for said carrier constructed so as to bodily raise and lower the carrier and cause it to assume a discharge position with 50 its front end tilted downwardly towards the top roll, and thereafter move rearwardly far enough to clear said work supporting means during the downward stroke of said carrier.

55 2. A plate lifting mechanism for rolling mills, comprising a work supporting means arranged at the rear of the rolls of the mill for receiving the work discharged from the rolls, a carrier for moving the work upwardly into a position to be discharged forwardly 60 over the top roll of the mill, and an operating mechanism constructed so as to bodily raise and lower the carrier, cause the carrier to travel in close proximity to the top roll of the mill during its upward 65 stroke and reach a discharge position, where-

in it is tilted downwardly towards the top roll, and thereafter move rearwardly during its downward stroke far enough to clear said work supporting means.

3. A plate lifting mechanism for rolling 70 mills, comprising a work supporting means arranged at the rear of the rolls of the mill for receiving the work discharged from the rolls, a carrier, and an operating mechanism for the carrier for causing the carrier to move upwardly into proximity to the top roll of the mill, then move downwardly and rearwardly out of the path of said work supporting means and then move forwardly into 75 operative relationship with said work supporting means.

4. A plate lifting mechanism for rolling 80 mills, comprising a work supporting means arranged at the rear of the rolls of the mill, a carrier for moving the work upwardly 85 from said work supporting means into a position to discharge forwardly over the top roll of the mill, means for raising and lowering said carrier, means for reciprocating said carrier endwise while it is being raised and lowered, and means for enabling the operator in charge of the mill to render said carriage reciprocating means inactive without affecting the operation of said carrier 90 raising and lowering means.

5. A plate lifting mechanism for rolling 95 mills, comprising a work supporting means arranged at the rear of the rolls of the mill, a carrier adapted to receive the work from said supporting means and move the work upwardly into proximity to the top roll of the mill, a mechanism for raising and lowering the carrier, and a means capable of being coupled with said mechanism or disconnected from same for causing the carrier to move 100 rearwardly far enough during its downward stroke to clear said work supporting means.

6. A plate lifting mechanism for rolling 110 mills, comprising a carrier arranged at the rear of the rolls of the mill for receiving work discharged from the rolls and moving said work upwardly into proximity to the top roll of the mill, a frame, counterweighted rock levers on said frame, a support for the carrier pivotally connected to said levers and 115 adapted to be moved bodily upwardly and then downwardly, and means for tilting or rocking the carrier relatively to said carrier support while said carrier is moving upwardly so as to cause said carrier to be arranged in a position with its front end tilted 120 downwardly towards the top roll of the mill.

7. A plate lifting mechanism for rolling 125 mills, comprising a carrier arranged at the rear of the rolls of the mill, a support on which said carrier is rockably mounted, means for bodily raising and lowering said support, and an adjustable means for tilting the front end of the carrier downwardly more or less towards the top roll of the mill, 130

during the upward travel of the carrier support.

8. A plate lifting mechanism for rolling mills, comprising a carrier arranged at the rear of the rolls of the mill, a support on which said carrier is rockably mounted, an operating mechanism for bodily raising and lowering said support, and a member pivotally connected to said mechanism and to the rear end of the carrier for holding the carrier in a substantially horizontal position during the first portion of its upward stroke and for tilting the front end of the carrier downwardly towards the top roll of the mill before said carrier reaches its discharge position.

9. A plate lifting mechanism for rolling mills, comprising a frame arranged at the rear of the rolls of the mill, pairs of counter-weighted rock levers on said frame, means for rocking said levers upwardly and downwardly, a support carried by said levers, a carrier rockably mounted on said support, and a member pivotally connected to the rear end of said carrier and to angularly-disposed portions on one of said pairs of rock levers.

10. A plate lifting mechanism for rolling mills, comprising a frame arranged at the rear of the rolls of the mill, pairs of counterweighted rock levers on said frame, means for rocking said levers upwardly and downwardly, a support carried by said levers, a carrier rockably mounted on said support, a member pivotally connected to the rear end of said carrier and to angularly-disposed portions on one of said pairs of rock levers, and co-operating means on said member and carrier, capable of being adjusted, for causing the carrier to assume a downwardly-inclined position when it is at the end of its upward stroke.

11. A plate lifting mechanism for rolling mills, comprising a frame arranged at the rear of the rolls of the mill, pairs of counterweighted rock levers on said frame connected so as to move in unison, a support pivotally connected to said levers, adjustable, angularly-disposed extensions on one pair of levers, a carrier rockably mounted on said support, and a rock arm pivotally connected to the carrier and pivotally connected to said extensions.

12. A plate lifting mechanism for rolling mills, comprising a frame arranged at the rear of the rolls of the mill, pairs of counterweighted rock levers on said frame connected so as to move in unison, a support pivotally connected to said levers, adjustable, angularly-disposed extensions on one pair of levers, a carrier rockably mounted on said support, a rock arm pivotally connected to the carrier and pivotally connected to said extensions, and an adjustable means on said rock arm that is adapted to

engage a tail piece on the rear end of the carrier during the upward stroke of the carrier.

13. A plate lifting mechanism for rolling mills, comprising a frame arranged at the rear of the rolls of the mill, pairs of counterweighted rock levers on said frame connected so as to move in unison, a drive shaft rotatably mounted in said frame, means for transmitting movement from said drive shaft to said rock levers to raise and lower said levers, a support pivotally connected to the free ends of said levers, a carrier rockably mounted on said support, and an adjustable means between one pair of levers and the rear end of the carrier for sustaining the carrier and causing it to rock on said support when said support is being raised and lowered.

14. A plate lifting mechanism for rolling mills, comprising a carrier arranged at the rear of the rolls of the mill for receiving work discharged from said rolls, a support on which said carrier is reciprocatingly mounted, means for raising and lowering said support, and means for reciprocating the carrier relatively to said support while it is being raised and lowered.

15. A plate lifting mechanism for rolling mills, comprising a carrier arranged at the rear of the rolls of the mill, a support on which said carrier is reciprocatingly mounted, mechanism for raising and lowering said support, a means operated by said mechanism for causing the carrier to move rearwardly relatively to said support during the downward movement of said support, and a spring for moving the carrier in the opposite direction relatively to the support before said support reaches the end of its downward stroke.

16. A plate lifting mechanism for rolling mills, comprising a work supporting means arranged at the rear of the rolls of the mill, a carrier adapted to engage the work sustained by said work supporting means and move the work upwardly into proximity to the top roll of the mill, a support for said carrier, a mechanism for raising and lowering said support, and a means actuated by said mechanism for causing the carrier to reciprocate on said support during the downward stroke of the support and thus clear said work supporting means.

17. A plate lifting mechanism for rolling mills, comprising a carrier arranged at the rear of the rolls of the mill, a support for said carrier, mechanism for raising and lowering said support, means for reciprocating the carrier relatively to said support, and a coupling device under the control of the operator in charge of the mill for enabling said reciprocating means to be connected with or disconnected from said mechanism.

18. A plate lifting mechanism for rolling

10 mills, comprising a carrier arranged at the rear of the rolls of the mill, a support on which said carrier is reciprocatingly mounted, a mechanism for raising and lowering said support, a toggle operated by said mechanism for moving the carrier in one direction relatively to said support, a spring which tends to resist movement of the carrier in this direction, and means for breaking said toggle or rendering it inactive before said support reaches the end of its downward stroke.

15 19. A plate lifting mechanism for rolling mills, comprising a carrier arranged at the rear of the rolls of the mill, a support on which said carrier is reciprocatingly mounted, a mechanism for raising and lowering said support, a rock arm pivotally connected with said mechanism and with the rear end 20 of the carrier, a transmission member detachably connected with said rock arm, a toggle combined with said mechanism and with said transmission member for moving said transmission member rearwardly during the downward stroke of the support, means for rendering said toggle inactive during the downward stroke of said support, and a spring which causes said transmission member to move forwardly after said 30 toggle has been rendered inactive.

25 20. A plate lifting mechanism for rolling mills, comprising a carrier arranged at the rear of the rolls of the mill, a support on which said carrier is reciprocatingly mounted, pairs of front and rear counterweighted rock levers pivotally connected to said support for raising and lowering the same, angularly-disposed extension members on the rear rock levers, a rock arm pivotally connected to said extension member and to the rear end of the carrier, an oscillating transmission member, a coupling pin for detachably connecting said member with said rock arm, an angularly-disposed extension member 40 on one of said front rock levers combined with a toggle that causes said transmission member to swing rearwardly during the downward stroke of the support, a spring for moving the transmission member forwardly, and means for causing said toggle to be rendered inactive during the 45 downward stroke of said support.

50 21. A plate lifting mechanism for rolling mills, comprising a carrier arranged at the rear of the rolls of the mill, a support for said carrier, rollers on said support, elongated guideways on the carrier which receive said rollers, mechanism for raising and lowering said support, a rock arm pivotally connected with said mechanism and with the rear end of the carrier, a spring 55 connected with said support and with said rock arm for resisting movement of the carrier rearwardly with relation to said support, and means actuated by the operating 60

mechanism for said support for swinging said rock arm rearwardly during part of the downward stroke of said support.

22. A plate lifting mechanism for rolling mills, comprising a work supporting means 70 arranged at the rear of the rolls of the mill, a carrier for moving the work upwardly off said supporting means, a support on which said carrier is reciprocatingly mounted, mechanism for raising and lowering said 75 support and causing said carrier to reciprocate longitudinally of same, and means for permitting the front end of the carrier to swing upwardly in the event it accidentally engages said work supporting means during the downward stroke of the carrier support.

23. A plate lifting mechanism for rolling mills, comprising a work supporting means 80 arranged at the rear of the rolls of the mill, a carrier for moving the work upwardly off said work supporting means, a carrier support, a hinged member on said support provided with rollers that are arranged in elongated guideways in the carrier, and mechanism for raising and lowering the carrier support and causing the carrier to reciprocate relatively to same during the downward stroke of said carrier support.

24. A plate lifting mechanism for rolling 90 mills, comprising a work supporting means arranged at the rear of the rolls of the mill, a carrier, means for raising and lowering said carrier and causing it to move rearwardly far enough to clear said work supporting means during the downward stroke of the carrier, and an operating mechanism for said work supporting means constructed to normally hold said means in an inclined position, and cause it to swing downwardly into substantially a horizontal position at about the time the carrier moves upwardly to remove the work from said work supporting means.

25. A plate lifting mechanism for rolling 110 mills, comprising work supporting arms arranged at the rear of the rolls of the mill, a vertically movable carrier provided at its front end with slots so as to permit the carrier to move upwardly past said work supporting arms and remove the work therefrom, means for moving the carrier rearwardly away from said work supporting arms so as to clear the same on the downward stroke of the carrier, and an operating means 115 for said work supporting arms constructed so as to normally hold said arms in an upwardly inclined position and cause them to swing downwardly into a substantially horizontal position at about the time the carrier travels upwardly past said arms.

26. A plate lifting mechanism for rolling 120 mills, comprising work supporting arms arranged in spaced relation at the rear of the rolls of the mill, a rock shaft to which said 130

- arms are connected, means for operating said rock shaft for raising and lowering said arms, a carrier for moving the work upwardly from said arms provided with slots 5 so as to permit the carrier to move upwardly past said arms, a support for said carrier, means for raising and lowering said support, and means for causing said carrier to move rearwardly relatively to said support during 10 part of the downward stroke of the support and thereafter move forwardly into a position under the work sustained by said work supporting arms.
27. A plate lifting mechanism for rolling mills, comprising a plurality of work supporting arms arranged in spaced relation at the rear of the rolls of the mill, a rock shaft to which said arms are connected, means for actuating said rock shaft to raise and lower 15
- said arms, a frame, pairs of rock levers on said frame connected to move in unison, counterweights attached to one end of said rock levers, a support pivotally connected to the opposite end of said rock levers, a hinged plate on said support provided with rollers, 20 a carrier provided with elongated guideways that receive said rollers, a rock arm pivotally attached to the rear end of said carrier and joined to angularly-disposed extension members on one pair of rock levers, a spring 25 attached to said carrier support and to said rock arm, and a means actuated by one of said rock levers for moving said rock arm rearwardly so as to cause the carrier to move rearwardly far enough to clear the work 30 supporting arms while the carrier support is moving downwardly.

THOMAS McCABE.
